Des. 240,753
Patented July 27, 1976

240,753

FLYING TOY

Davey L. Langston, 3616 Mount Vernon,
Fort Worth, Tex. 76103

Filed May 23, 1975, Ser. No. 580,369

Term of patent 14 years

Int. Cl. D21—02

U.S. Cl. D34—15 W

FIG. 1

FIG. 2

FIG. 3

FIG. 4

FIG. 1 is a front elevational view of a flying toy with wings extended showing my new design;

FIG. 2 is a right side elevational view thereof;

FIG. 3 is a top plan view thereof; and

FIG. 4 is a bottom plan view thereof.

I claim:

The ornamental design for a flying toy, substantially as shown.
